UNITED STATES PATENT OFFICE.

EGON LOTHAR SCHMITZ, OF NEW YORK, N. Y., ASSIGNOR TO EBERHARD FABER PENCIL COMPANY, OF BROOKLYN, NEW YORK, A CORPORATION OF NEW YORK.

DESIGN FOR A DISPLAY-RACK.

No. 38,838.

Specification for Design.

Patented Sept. 24, 1907.

Application filed May 14, 1907. Serial No. 373,679. Term of patent 14 years.

To all whom it may concern:

Be it known that I, EGON LOTHAR SCHMITZ, a citizen of the United States, residing in the borough of Brooklyn, in the county of Kings, city and State of New York, have invented a new, original, and ornamental Design for a Display-Rack, as shown in the accompanying drawing.

Figures 1 and 2 are perspective views of a display-rack showing my new design.

I claim:
The ornamental design for a display-rack as shown.

EGON LOTHAR SCHMITZ.
